COATING COMPOSITION FOR SUBBING
POLYSTYRENE FILMJay J. Uber, South Hadley, Mass., assignor to
The Plastic Coating CorporationNo Drawing. Filed Sept. 18, 1961, Ser. No. 138,567
8 Claims. (Cl. 106—128)

This invention relates to a coating composition for use in the production of a photographic film having a polystyrene base sheet.

Polystyrene film has heretofore been proposed for use as a photographic film support and is finding increasing commercial use for this purpose. A serious problem has heretofore been presented in securing a firm bond between the surfaces of a polystyrene base sheet and the light-sensitive coating of a gelatin-silver halide emulsion. Various solutions have been proposed for the solution of this problem.

One proposed solution has been the application of an intermediate subbing layer consisting of two or more coatings of different compositions. This solution to the problem has the disadvantage of requiring two or more coating operations to form the subbing, prior to the application of the light-sensitive coating, thereby increasing the cost of the product.

Another solution to the problem has involved the substitution of a special light-sensitive coating for the conventional gelatin-silver halide emulsion. This solution to the problem has the dual disadvantage of requiring a material and complex deviation from the normal procedures for the application of the conventional gelatin-silver halide emulsion coatings, with increased cost arising both from the more expensive ingredients used in the special light-sensitive coating composition and the complex procedure involved in the formulation of the light-sensitive coating composition. A third solution to this problem has involved a combination of the foregoing alternative solutions which combines the economic disadvantages of each of those alternatives.

Specific examples of each of these alternative solutions to this problem are described by U.S. 2,816,027, issued December 10, 1957, to Thomas H. Farrell et al. While describing in considerable detail these alternative solutions to the problem, that patent states that for certain purposes it is not necessary to apply a subbing to polystyrene sheeting before coating it with a photographic emulsion, especially where the photographic film is to be employed at comparatively high relative humidity. However, as a practical matter, the application of a subbing coating to a polystyrene base sheet is essential in the production of photographic film intended for any normal usage.

It will be understood that the term "subbing" is used in this specification in its usually accepted sense to mean an intermediate film or coating on the surface of a base sheet or film which bonds a photographic gelatin-silver halide emulsion to the surface of the base sheet or film.

In my copending U.S. patent application, Serial No. 826,433, filed July 13, 1959, which matured into U.S. 3,010,838, and, of which this application is a continuation-in-part, I have disclosed a coating composition for application to a polystyrene base sheet or film in a single coating operation to form a subbing which will receive

2

and firmly bond a conventional light-sensitive gelatin-silver halide coating to the polystyrene base sheet or film. The coating composition disclosed by that application comprises gelatin, nitrocellulose, phenol, a cresol, or a mixture of cresols, and acetic acid dispersed in a suitable volatile solvent for nitrocellulose. It may contain about 0.5% to about 2.0%, by weight, of gelatin and preferably contains an amount within the range of about 0.75%, to about 1.5%, by weight. It may contain an amount of nitrocellulose within the range of about 0.25% to about 2.25%, by weight, and preferably within the range of about 0.75%, by weight, to about 1.5%, by weight. It will contain an amount of phenol within the range of about 1.0% to about 5.0%, by weight, and preferably 15 2.0% to about 4.0%, by weight. The acetic acid content of the composition may be within the range of 1.5% to about 6.0%, by weight, and preferably will be within the range of about 2.0%, to about 4.0%, by weight.

A substantial proportion of the phenol, cresol or the mixture of cresols in this composition appears to remain in the coating film after the evaporation of the volatile solvents therefrom and increases the adhesion of the coating film to the surface of the polystyrene sheet or film. Although this composition is a definite advance in the subbing of polystyrene sheets or films, it has the disadvantage of producing a product which has a residual odor of phenol or cresol, as the case may be. Further, its preparation and use in the coating of the polystyrene film or sheet involves the hazard of handling phenol, cresol or 20 the mixture of cresols, which are inherently dangerous chemicals.

I have found that a coating composition which is adapted for application to a polystyrene sheet or film in a single coating operation to form a subbing which will receive and firmly bond a conventional light-sensitive gelatin-silver halide coating to the polystyrene base sheet or film, which is a definite improvement over the composition disclosed by my copending application, Serial No. 826,433, may be prepared by the substitution of a liquid low molecular weight styrenated-phenol polymer for all or a significant part of the phenol, the cresol or the mixture of cresols in the coating composition of that copending application.

The coating composition in accordance with this invention comprises gelatin, nitrocellulose, liquid low molecular weight styrenated-phenol polymer and acetic acid dispersed in a suitable volatile solvent for nitrocellulose. It may contain about 0.5% to about 2.0%, by weight, of gelatin and preferably contains an amount within the range of about 0.5% to about 1.5%, by weight. It may contain an amount of nitrocellulose within the range of about 0.25% to about 2.25%, by weight, and preferably within the range of about 0.75%, by weight, to about 1.5%. It will contain an amount of styrenated phenol within the range of about 0.5%, by weight, to about 3.5%, by weight. The acetic acid content of the composition may be within the range of 1.5% to about 6.0%, by weight, and preferably will be within the range of about 2.0% to about 4.0%, by weight. The acetic acid in this composition acts as a solvent for the gelatin therein and permits its solution in the anhydrous solvent for the nitrocellulose. It is a volatile constituent of the composition.

The remainder of this composition consists essentially of a volatile solvent for the particular type of nitrocellulose which is included in the composition and is preferably a volatile solvent mixture for the nitrocellulose which includes toluene as a volatile non-solvent diluent in the mixture. The toluene in the volatile solvent mixture appears to have a definite action in improving the adhesion of the film deposited by the composition of the polystyrene sheet or film. The formulations of suitable volatile solvent mixtures for the conventional types of nitrocellulose which are included in this composition are well known to the prior art.

The liquid low molecular weight styrenated phenol polymer which forms an essential component of my improved composition is a polymerized alkyl aryl phenol. A commercial product identified by the trademark "Wing-Stay S" is entirely suitable for use in this composition. The physical properties of "Wing-Stay S" are given in Table I.

TABLE I

Density:	
Gms./ml. -----	1.08
Lbs./gal. -----	9.0
Viscosity (Stormer viscosimeter, 400 gms., at 25° C.), r.p.m. -----	15-55
Refractive index, N_d 25° C. -----	1.5985-1.6020
Flash point (Cleveland Open Cup Method), ° F. -----	360
Color (Gardner) -----	8 or less

The viscosity of this polymer is an index of the extent of its polymerization.

It is a well-recognized fact that the strength of nitrocellulose varies with its viscosity characteristic with the strength falling off rapidly with the lower viscosity types. Despite this well-known fact, I have found in the case of a subbing film deposited from the composition of this invention, that its bonding strength increases when the lower viscosity types of nitrocellulose are used in the composition. A nitrocellulose having a viscosity characteristic of 15 seconds gives very poor adhesion between a photographic gelatin-silver halide emulsion film and a polystyrene surface. It is desirable to use a nitrocellulose in this coating composition which has a viscosity characteristic within the range of about 10 centipoises to about 5 seconds, and I prefer to use a nitrocellulose having a viscosity characteristic of within the range of about 10 centipoises to about $\frac{1}{2}$ second. A 15 centipoise nitrocellulose has been found to give excellent results in this composition. The viscosity characteristic of a nitrocellulose of a type higher than $\frac{1}{4}$ second may be measured by the standard falling ball method described by ASTM specification D301-50, while viscosity characteristics of $\frac{1}{4}$ second or lower can be conveniently measured by the use of a capillary viscometer described, for example, on page 30 of the "Hercules Nitrocellulose Handbook," published by Hercules Powder Company. The nitrocellulose may be of the RS type (11.8 to 12.2% nitrogen) or of the SS type (10.9 to 11.2% nitrogen).

The polystyrene which is subbed by the use of the composition of this invention to form the base sheet or film of a photographic film is of the flexible type which may be produced by methods known in the art. U.S. Patent 2,074,285, issued Mar. 16, 1937, to E. Studt et al., discloses a method for the production of such sheets. The polystyrene sheet or film may be of any desired thickness and will usually have a thickness within the range of about 0.002 inch to 0.020 inch.

The photographic silver halide emulsion which is applied over the subbing on the polystyrene is of the conventional type. Typical photographic silver halide emulsions include silver chloride, silver bromide, silver iodide, silver bromide, silver chlorobromide and silver chlorobromide emulsions. The carrier for the silver halide is gelatin.

The coating composition in accordance with this invention is specifically illustrated by the following example:

EXAMPLE I

Gelatin -----	0.93
Glacial acetic acid -----	3.54
Toluene -----	5.22
n-Butyl alcohol -----	8.80
Nitrocellulose, 18 cps. (70%) -----	2.06
Acetone -----	1.67
10 Ethanol -----	0.15
Butyl acetate -----	0.17
Methanol -----	74.28
Phenol -----	
Liquid styrenated phenol polymer -----	3.18
	150.00

The composition illustrated by Example I may be applied to polystyrene film in an amount within the range of about 6.5 lbs. to about 16.5 lbs. (wet coating weight) per thousand square feet and preferably within the range of about 8 lbs. to about 10 lbs. (wet coating weight) per thousand square feet.

As will be understood from the foregoing, the amounts of gelatin, of nitrocellulose, of glacial acetic acid and of the liquid styrenated phenol polymer shown by Example I may be varied. In general, the ratio of nitrocellulose to gelatin should be within the range of about 0.5 to 1.5 parts by weight for each part by weight of gelatin. Table II gives ranges of proportions which may be used in the coating composition.

TABLE II

Ranges of proportions of ingredients for coating composition for subbing polystyrene film

	Percent by wt.
Gelatin -----	0.50-1.50
Nitrocellulose (viscosity with the range of 10 centipoises to $\frac{1}{2}$ second) -----	0.25-2.25
Glacial acetic acid -----	1.50-6.00
Liquid styrenated phenol polymer -----	0.5-3.5
Volatile solvent mixture -----	The remainder

In the range of compositions shown by Table II, no phenol, cresols or mixtures of cresols are included in the composition. As already noted hereinbefore, the liquid low molecular weight styrenated phenol polymer may be used as a replacement for all or a part of the phenol, the cresol or the mixture of cresols in the coating composition of my copending application, Serial No. 826,433.

To obtain the beneficial action of the liquid styrenated phenol polymer in improving the bonding strength, it is desirable to use at least 0.1% and, preferably, 0.5%, by weight, as a replacement for a portion of the phenol, cresol or mixture of cresols. In general, one part of the liquid low molecular weight styrenated phenol polymer is as effective as two parts by weight of the phenol, cresol or mixture of cresols, but no more than 3.5% of the liquid low molecular weight styrenated phenol polymer should be included in the composition since a higher proportion will soften the polystyrene base film. Therefore, an amount of phenol, cresol or mixture of cresols within the range of 0.9%, by weight, to 4.9%, by weight, may be used with an amount of the liquid low molecular weight styrenated phenol polymer within the range of 0.1%, by weight, to 3.5%, by weight. Preferably, an amount of the liquid low molecular weight styrenated phenol polymer within the range of 0.5%, by weight, to 3.5%, by weight, is used in a mixture with an amount of phenol, cresol or a mixture of cresols within the range of 0.5%, by weight, to 4.5%, by weight. The cresol which may be used in this mixture may be ortho cresol, meta cresol, para cresol or a mixture thereof.

When applied to the surface of a polystyrene sheet or film, the coating composition in accordance with this in-

vention deposits a subbing coating which has definitely stronger adhesion to the surface of the polystyrene than those deposited by the prior art subbing compositions. This subbing coating has even stronger adhesion to the surface of the polystyrene sheet or film than that of the subbing coating deposited by the coating composition described by my copending application, Serial No. 826,433. The improved adhesion of the subbing coating deposited by a representative composition of this invention as compared with those deposited by a representative prior art coating composition and by a coating composition representative of those described by my copending application is illustrated by the comparative tests described below.

Coating compositions having compositions given by Table III were applied evenly over the surface of sheets of polystyrene film in an amount equivalent to 8 to 10 lbs. of the solutions per thousand square feet of film. The sheets of film coated with these compositions were then dried for three minutes at 160° F. in a circulating hot air oven.

TABLE III

Coating compositions for subbing polystyrene film used for comparative tests of the adhesion of the coating deposited therefrom for a polystyrene surface

	Example I	Example II	Example III
Gelatin.....	0.93	0.93	0.93
Glacial Acetic Acid.....	3.54	3.54	3.54
Toluene 4.30+ .92.....	5.22	5.22	5.22
n-Butyl alcohol.....	8.80	8.80	8.80
Nitrocellulose—18 cps. (70%).....	2.06	2.06	2.06
Acetone.....	1.67	1.67	1.67
Ethanol.....	0.15	0.15	0.15
Butyl Acetate.....	0.17	0.17	0.17
Methanol.....	74.28	74.28	74.28
Phenol.....	3.18	3.18	3.18
Liquid Styrenated Phenol Polymer.....	3.18	3.18	3.18
	100.00	100.00	96.82

As already noted, Example I is representative of the coating compositions of this invention. Example II is representative of those disclosed by my copending application, Serial No. 826,433, while Example III is a representative prior art coating composition for subbing polystyrene film.

Each of the sheets of polystyrene film coated by the compositions of Examples I, II and III were dipped into an aqueous solution of a green dye for three minutes and the adhesion of the coating for the surface of the polystyrene film tested by the application of a six inch strip of "Scotch" brand cellophane tape to the surface of the coating which was then removed by a sharp jerk. The adhesion of the coating for the surface of the polystyrene film was rated as "poor" if all or most of the coating was removed from the polystyrene surface by the "Scotch" brand cellophane tape. The adhesion was rated as "fair" if a portion, but not all, of the coating was removed by the "Scotch" brand cellophane tape. The adhesion was rated as "good" if none of the coating was removed by the "Scotch" brand cellophane tape.

In these comparative tests, the coating deposited from the composition of Example I received a rating of "good." The coating composition deposited by the coating composition of Example II was rated as "fair," while that deposited from the composition of Example III was given a rating of "poor."

In the foregoing, various details have been given to fully explain the nature of this invention. However, it will be fully understood that various changes and modifications can be made in those details without departing from the spirit of this invention or the scope of the claims which follow.

I claim:

1. A coating composition consisting essentially of about 0.5%, by weight, to about 2.0%, by weight, of gelatin;

about 0.5%, by weight, to about 2.25%, by weight, of nitrocellulose having a viscosity characteristic no higher than 5 seconds as measured by the standard method ASTM Specification D301-50; about 1.5% by about 5 6.0%, by weight, of acetic acid; about 0.5%, by weight, to about 3.5%, by weight, of a liquid low molecular weight styrenated phenol polymer and a volatile organic solvent for said nitrocellulose.

2. A coating composition consisting essentially of about 10 0.5%, by weight, to about 2.0%, by weight, of gelatin; about 0.5%, by weight, to about 2.25%, by weight, of nitrocellulose having a viscosity characteristic no higher than 1/2 second as measured by the standard method ASTM Specification D301-50; about 1.5% by about 15 6.0%, by weight, of acetic acid; about 0.5%, by weight, to about 3.5%, by weight, of a liquid low molecular weight styrenated phenol polymer and a volatile organic solvent for said nitrocellulose.

3. A coating composition consisting essentially of about 20 0.5%, by weight, to about 2.0%, by weight, of gelatin; about 0.5%, by weight, to about 2.25%, by weight, of nitrocellulose having a viscosity characteristic no higher than 5 seconds as measured by the standard method ASTM Specification D301-50; about 1.5% by about 25 6.0%, by weight, of acetic acid; about 0.5%, by weight, to about 3.5%, by weight, of a liquid low molecular weight styrenated phenol polymer and a volatile organic solvent for said nitrocellulose which is a mixture containing toluene as a non-solvent diluent.

4. A coating composition consisting essentially of about 30 0.5%, by weight, to about 2.0%, by weight, of gelatin; about 0.5%, by weight, to about 2.25%, by weight, of nitrocellulose having a viscosity characteristic no higher than 1/2 second as measured by the standard method ASTM Specification D301-50; about 1.5% by about 35 6.0%, by weight, of acetic acid; about 0.5%, by weight, to about 3.5%, by weight, of a liquid low molecular weight styrenated phenol polymer and a volatile organic solvent for said nitrocellulose which is a mixture containing toluene as a non-solvent diluent.

5. A coating composition consisting essentially of about 40 0.5%, by weight, to about 2.0%, by weight, of gelatin; about 0.5%, by weight, to about 2.25%, by weight, of nitrocellulose having a viscosity characteristic no higher than 5 seconds as measured by the standard method ASTM Specification D301-50; about 1.5% by about 45 6.0%, by weight, of acetic acid; about 0.1%, by weight, to about 3.5%, by weight, of a liquid low molecular weight styrenated copolymer; about 0.9%, by weight, to 4.9%, by

50 weight, of a material selected from a group consisting of phenol, ortho cresol, meta cresol, para cresol and a mixture of cresols and a volatile organic solvent for said nitrocellulose.

6. A coating composition consisting essentially of about 55 0.75%, by weight, to about 2.0%, by weight, of gelatin; about 0.75%, by weight, to about 1.5%, by weight, of nitrocellulose having a viscosity characteristic of no higher than 1/2 second as measured by the standard method ASTM Specification D301-50; about 2.0%, by weight, of 60 acetic acid; about 0.5%, by weight, to about 3.5%, by weight, of a liquid low molecular weight styrenated phenol polymer and a volatile organic solvent for said nitrocellulose which is a mixture containing toluene as a non-solvent diluent.

7. A coating composition consisting essentially of about 65 0.5%, by weight, to about 2.0%, by weight, of gelatin; about 0.5%, by weight, to about 2.25%, by weight, of nitrocellulose having a viscosity characteristic no higher than 1/2 second as measured by the standard method ASTM Specification D301-50; about 1.5% by about 70 6.0%, by weight, of acetic acid; about 0.5%, by weight, to about 3.5%, by weight, of a liquid low molecular weight styrenated phenol polymer; about 0.5% to about 4.5% of a material selected from the group consisting of phenol, ortho cresol, meta cresol, para cresol and mix-

tures of cresols, and a volatile organic solvent for said nitrocellulose.

8. A coating composition consisting essentially of about 0.5%, by weight, to about 2.0%, by weight, of gelatin; about 0.5%, by weight, to about 2.25%, by weight, of nitrocellulose having a viscosity characteristic no higher than $\frac{1}{2}$ second as measured by the standard method ASTM Specification D301-50; about 1.5% by about 6.0%, by weight, of acetic acid; about 0.5%, by weight, to about 3.5%, by weight, of a liquid low molecular weight styrenated phenol polymer; about 0.5% to about 4.5% of a material selected from the group consisting
